(57) **CLAIM**

The ornamental design for a holder for epinephrine injector, as shown and described.

DESCRIPTION

FIG. 1 is a front, right, top perspective view of a holder for epinephrine injector showing the new design.

FIG. 2 is a front, right, bottom perspective view thereof.

FIG. 3 is a front, right, top perspective view thereof.

FIG. 4 is a rear, right, top perspective view thereof.

FIG. 5 is a rear, right, top perspective view thereof.

FIG. 6 is a rear, right, bottom perspective view thereof.

FIG. 7 is a front, left, top perspective view thereof.

FIG. 8 is a front, left, bottom perspective view thereof.

FIG. 9 is a front, left, top perspective view thereof.

FIG. 10 is a rear, left, top perspective view thereof.

FIG. 11 is a rear, left, top perspective view thereof.

FIG. 12 is a rear, left, bottom perspective view thereof.

FIG. 13 is a front view thereof.

FIG. 14 is a rear view thereof.

FIG. 15 is a left side view thereof.

FIG. 16 is a right side view thereof.

FIG. 17 is a bottom view thereof.

FIG. 18 is a top view thereof.

FIG. 19 is a sectional view thereof, along line 19-19 in FIG. 13.

FIG. 20 is a sectional view thereof, along line 20-20 in FIG. 13.

FIG. 21 is a sectional view thereof, along line 21-21 in FIG. 17.

FIG. 22 is a sectional view thereof, along line 22-22 in FIG. 17.

FIG. 23 is a sectional view thereof, along line 23-23 in FIG. 17.

FIG. 24 is a sectional view thereof, along line 24-24 in FIG. 17; and,

FIG. 25 is a front, left, top perspective view thereof showing the device in use affixed to a mobile phone, holding an Auvi-QTM epinephrine injector in the larger top chamber and several credit cards in the smaller bottom chamber.

(Continued)

The evenly spaced broken lines depict portions of the holder for epinephrine injector and form no part of the claimed design.

The dot-dash broken lines depict cross-sectional location indicators for the holder for epinephrine injector and form no part of the claimed design.
